UNITED STATES PATENT OFFICE.

GEORGE W. RIVES, OF ROCHESTER, NEW YORK.

DESIGN FOR A FACE-PLATE FOR REGISTERS.

SPECIFICATION forming part of Design No. 21,124, dated October 20, 1891.

Application filed September 25, 1891. Serial No. 406,879. Term of patent 3½ years.

To all whom it may concern:

Be it known that I, GEORGE W. RIVES, of Rochester, in the county of Monroe and State of New York, have invented a certain new and useful Design for Face-Plates of Hot-Air Registers; and I do hereby declare that the following is a full, clear, and exact description of the same, reference being had to the drawing accompanying this application.

10 My design consists in the ornamental open-work or grating of the face-plate, as herein-after described.

The drawing shows a plan or face view of the plate.

15 A indicates the face-plate, which is of rectangular or square form. The grating is composed of alternate circular figures *a a* and cross-shaped figures *b b*, connected by diagonal bars *c c*, which run in reverse directions.

20 The circular figures *a a* are composed of two circles, one within the other, with an ogee-

shaped central connection *d*. The sides of cross-shaped figures *b b* are convex, as shown, and in the center is a star *f* with many points. The whole presents an ornamental appearance, in which the two sets of figures and the diagonal bars stand in relief. 25

Having described my new design, I claim—

The design for face-plates of hot-air registers, consisting of the circular figures *a a*, the cross-shaped figures *b b*, with a star in the center, and the diagonal bars *c c*, running in reverse directions through the figures, as herein shown and described. 30

In witness whereof I have hereunto signed my name in the presence of two subscribing witnesses. 35

GEO. W. RIVES.

Witnesses:

R. F. OSGOOD,

CHAS. A. WIDENER.
